KNITTING MACHINE AND METHOD OF
KNITTING

Robert H. Lawson, Pawtucket, and Augustin Gagne, Central Falls, R. I., assignors to Hemphill Company, Central Falls, R. I., a corporation of Massachusetts

Application December 24, 1932, Serial No. 648,817

19 Claims. (Cl. 66—137)

This invention relates to reverse plating and more especially to reverse plating with three or more threads or yarns. As herein disclosed, the mechanism for effecting the reverse plating is applied to a knitting machine of the type disclosed in the patent to Hemphill 933,443, September 7, 1909, although the invention is not limited to a knitting machine having a rotary needle cylinder and furthermore is not limited to hosiery knitting machines nor to knitting machines having a circular series of needles.

In the drawings:

Fig. 1 is a view in elevation of a portion of a knitting machine with the improvements applied; Fig. 2 is a plan view of the parts shown in Fig. 1;

Fig. 3 is a view of the machine in end elevation;

Fig. 4 is a view in rear elevation of a portion of the machine;

Fig. 4a is a view in side elevation showing the drum of Fig. 4;

Fig. 5 is a view in elevation and partly in section, of that portion of the mechanism above the circular base;

Figs. 6 and 7 are elevational views taken at right angles to one another showing the means for effecting the periodic changes in the relative positions of the two plating threads;

Figs. 8, 9, 10 and 11 are detail views of the means disclosed in Figs. 6 and 7;

Fig. 12 is an enlarged plan view of a portion of the mechanism shown in Fig. 2;

Figs. 13 and 14 are respectively fragmentary plan and elevational views showing the immediate control for reversing the relative positions of the plating threads;

Fig. 15 is a fragmentary view of the latch ring showing the plating thread carrier in front elevation, in an elevated, inoperative position;

Fig. 16 is a fragmentary view similar to Fig. 15 but showing the thread-carrier at right angles to the position shown in Fig. 15;

Fig. 17 is a fragmentary view of the latch ring, showing the two plating threads in one of their relative positions;

Fig. 18 is a view similar to Fig. 17 but showing the two plating threads in the other of their relative positions;

Fig. 19 is a detail view of a yarn lever;

Figs. 20 and 21 are fragmentary views of the portion of the ring comprising the mouthpiece, said views also showing a body and two plating threads being fed to the needles of a knitting machine, Fig. 20 showing one body thread being

fed to the needles and Fig. 21 showing another;

Figs. 22 and 23 are similar to Figs. 20 and 21 respectively, but show the plating relations of a body and plating thread as having been reversed in the needle hooks by some well known reverse plating means;

Fig. 24 is a detail view of a needle showing the position of three threads in the needle hook and corresponding to Fig. 20; and

Fig. 25 is a view similar to Fig. 24 but corresponding to Fig. 22.

The knitting machine indicated generally by the numeral 1 is provided with a needle cylinder 2 within the tricks or grooves of which are mounted needles 2' which slide to and from knitting position in the usual manner. Surmounting the needle cylinder 2 is a sinker head 3 of usual construction. The frame of the machine includes a circular base 4 within which is mounted a so-called ring gear (not shown) which imparts continuous rotary or reciprocatory movements to the needle cylinder 2 in a manner common to hosiery knitting machines. Mounted upon the upper surface of the circular base 4 is the usual widening pick bracket 5 and diametrically opposite thereto is a cam plate 6 which surrounds the needle cylinder and is carried by a vertically adjustable bar 6'. Upon the upper surface of cam plate 6 are mounted the various cams for controlling the movements of the needles, the cams 30 including the usual cams carried by the cam block 7 upon which are mounted narrowing picks 8. Instep cams 9 are mounted upon a suitable bracket 10 itself attached to the cam plate 6, the cams thereof being operated in the usual manner 35 to elevate the long butt needles prior to the knitting of heels and toes and to restore such needles to a knitting level at the completion of the knitting of heels and toes. Spaced from the cam block 7 is a bracket 11 connected to a suitable 40 part of the machine frame upon which bracket are mounted a series of cam discs 12 adapted selectively to control the radial positions of a series of plungers 13 which in turn act upon jacks or other elements which cause sinkers selectively to effect reverse plating. The discs 12 are mounted upon a drum 14 which is provided with a ratchet 15 periodically engaged by a pawl means 16 whereby the discs 12 variably actuate their respective plungers 13. Pivotally mounted 45 (Fig. 2) upon a bracket 17 carried by the circular base 4, is the usual latch ring 18 which is provided with the usual mouth-piece extension 19 within which are pivotally mounted upon a pivot pin 20 yarn levers 21 and 22. Also mounted upon the 50

55

upper surface of the latch ring 18 at the mouth-piece 19 and upon the pivot pin 20 is a yarn lever 23, the said yarn lever (Figs. 13-19) including a member 24 in which is mounted a pin or shaft 25 to which is fastened a gear-like member 26 meshing with which is a segmental rack 27 which rack is pivoted intermediate its ends as at 28 to a bracket plate 29 which is fastened to and forms part of the yarn lever 23. The rack 27 is provided with an arm (Fig. 2) to which is pivotally connected at 30 a link 31 which is slideable and is guided in its sliding movements by means of a bracket 32 attached to the upper surface of plate 29. The segmental rack 27 is moved to the full line position of Fig. 13 by means about to be described, against the tension of the spring 32' which is attached at one end to one arm of the rack 27 and at its other end to plate 29.

In Figs. 1, 2, 3 and 5-14 inclusive, the actuating means for periodically and automatically controlling the movements of the rack to and from the positions shown in full and dotted lines, Fig. 13, are shown. The means for moving rack 27—and as a consequence thereof oscillating the gear 26 and the pin or shaft 25 to which it is connected, thereby to cause either the eye 33 or the eye 34, both of which are connected to the shaft 25, to maintain its thread in advance of the other thread—includes one arm 35 of a lever which arm 30 terminates in a hub 36 made fast to a shaft 37 by means of a set screw 38. The arm 35 when in the position shown in Fig. 14 causes the eye 33 to position its thread in advance of the thread companion to the eyelet 34, but when the arm 35 is moved to the position shown in full lines, Fig. 5, the spring 32' causes the eyelet 34 to position its thread in advance of the thread passing through the eyelet 33. The arm 35 when in the position last named is in engagement with an adjustable stop screw 39 which is carried by a bracket 40 itself made fast to the cap plate 41 of yarn lever box 42. The shaft 37 is supported in bearings in upstanding lugs 43, 44 carried by the plate 41, and the other end of the shaft 37 which projects beyond the bearing lug 44 has rigidly connected thereto a depending lever arm 45, a set screw 46 constituting the rigid connection between the shaft 37 and the hub 41 of the arm 45. The depending end of the arm 45 terminates in a hub 48 through which passes a pin 49 the projecting end of which is received within a bifurcation 50 of a lever 51 which lever is pivoted intermediate its ends at 52 to the yarn lever box 42 and at its lower end is pivotally connected at 53 to an adjustable link 54 which link in turn is pivotally connected at its other end at 55 to one arm 56. The arm 56 constitutes one arm of a lever said arm being rigidly connected to a shaft 57 as by means of a set screw 58. The other arm 59 of the said lever is spaced from the arm 56 and is also rigidly connected to the shaft 57 as by means of a set screw 60. The shaft 57 is pivotally supported in bearings comprising upright lugs 61 and 62 which are part of a bracket 63 which is made fast to an extension of the circular base 4. To the outer end of the arm 59 is pivotally connected as at 64 (Figs. 3 and 5) a depending link 65. Surrounding the link 65 below the base 4 is a coil spring 66, the spring at one end bearing against the lower side 70 of the base 4 and at its other end resting upon a collar 67 made fast to the link 65 intermediate its ends as by means of a set screw 68. The link 65 is made of two adjustably connected parts, the parts 65' thereof (Figs. 3, 6-11) being pivotally connected at 69 to a rod 70 to which is connected

a cam 71 by means of which cam the link 70 and connected parts are periodically actuated in a manner hereinafter to be more fully described.

The means for periodically actuating the link 70 and parts connected thereto comprise mechanism disclosed in detail in Figs. 2, 3, 4 and 6-12 inclusive. A ratchet wheel 72 is provided upon the periphery of which are a series of equally spaced teeth 73, the teeth being continuous excepting at 74 where a half-tooth is provided. The ratchet wheel is advanced by means of two pawls 75 and 76 which pawls are mounted upon a common axis 77 such axis being eccentrically disposed upon a side face of a wheel 78 which is mounted upon a shaft 79 which shaft passes through the machine frame being connected at the other side of the frame to a pinion 80 which is in mesh with the "104" gear 81. The pinion 80 is provided with twenty-six teeth whereas the gear 81 has one hundred and four teeth the result being that the shaft 79 and wheel 78 are rotated once during the knitting of each course and as a consequence thereof the pawls 75, 76 are actuated once for each course of knitting. The relative positions of the pawls and ratchet wheel 72 in Figs. 6 and 7 show the said parts at the end of the retiming operation during which the pawl 75 has advanced the ratchet wheel 72 in order to get the pattern lugs 82 which are mounted on one side face of the ratchet wheel 72 adjacent to the teeth thereof in proper circumferential position for the starting of the next stocking or half hose. During the retiming of the pattern disc or ratchet 72 a pawl idler 83 is in the position shown in Fig. 9 in which position an end 84 of the idler is underneath the pawl 76 which pawl reciprocates along the upper surface of the idler. After the pawl 75 has advanced the ratchet wheel 72 to the position shown in Fig. 6 the said pawl idly reciprocates along the space left by the missing portion of the tooth at 74 and the parts remain in the position shown in Fig. 6 until it is time to commence the knitting of the next stocking at which time the pawl idler 83 is specially actuated for which purpose the said idler is connected to a lever 85 which is pivoted at 86 and to the free end of which is pivotally connected at 87 a link 88 which at its upper end is pivotally connected at 89 (Figs. 3, 4 and 12) to a bell crank lever 90 which in turn is pivotally mounted upon the shaft 57 being restrained against endwise movement thereon by the lug 62 and by a collar 91 which is fastened to the shaft 57 as by means of a screw 92. To the other arm of the bell crank lever 90 is pivotally connected at 93 an adjustable link 94 which at its other end is pivotally connected at 95 to another bell crank lever 96 pivoted at 97 to a bracket 98 connected to the circular base 4. Pivotally connected at 99 to the other end of the bell crank lever 96 and depending therefrom is an adjustable link 100 pivoted at 101 to one arm of a lever 102 pivoted intermediate its ends. The other arm of the lever 102 terminates in a cam follower 103, normally maintained in engagement with the surface of a drum 104 or cams 105 and 106 which are mounted upon the surface thereof. The drum 104 is rigidly mounted upon the main cam shaft 107 of the machine which, preferably, is periodically advanced so as to move through 360 degrees during the knitting of each stocking or half hose.

When retiming of the ratchet wheel 72 has been completed and the knitting of the next stocking or half hose is about to commence, the cam drum 104 is advanced, the toe or follower 103 dropping off the cam 106 and onto the surface of the drum 75

104 at 108 which movement of the cam follower 103 permits the lever 85, through the connections hereinbefore described, to move from one position to a position where the pawl idler 88 is moved from under the pawl 76, whereupon the next advancing movement imparted to such pawl causes said pawl to advance the ratchet wheel 72 by engaging a tooth 73 thereof after which the pawls 75 and 76 both engage the wide teeth 73 and advance the ratchet wheel 72 once for each course of knitting. As the ratchet wheel 72 advances, either the pins or lugs 82 are brought opposite the cam 71 in which case the said cam is elevated and the rack 27—through the connections hereinbefore described—is moved to the position shown in Figs. 2 and 13 whereupon the thread passing through the eyelet 33 is moved to a position forward of the thread passing through the eyelet 34; or when the ratchet wheel 72 has been advanced to such a position that lugs 82 are not opposite or underneath the cam 71, such cam is permitted to drop, whereupon the thread passing through the eyelet 34 is moved to a position forward of the thread passing through the eyelet 33. The advancing movements of the ratchet wheel 72 continue, the pattern being repeated for each number of courses equal to the number of teeth 73; unless it be desirable to repeat the pattern for a number of courses less than that represented by the teeth 73, in which case pins or lugs 109, which are mounted in a circular series on one face of the ratchet wheel 72 and within the circle defined by the pins 82, are made discontinuous by leaving out one or two pins 109 as indicated at 110. As shown in Figs. 3 and 6 a cam 111 is rigidly attached to one face of a slideable rod 112 which rod is guided at one end by means of a pin or screw 113 passing through a slot 114 provided in the said rod, the pin or screw being in threaded engagement with a bracket 115. The rod 112 at its upper end is bifurcated as at 116 the arms thereof straddling a pin or screw 117 likewise secured to the bracket 115. The pin and slot connections just described permit the rod 112 to move longitudinally of the ratchet wheel 72 and likewise of the pawls 75 and 76. Adjacent to the upper end of the rod 112 there is fastened a pawl idler 118 which when in the position indicated in Fig. 6 limits the effective movement of the pawls 75 and 76 to that measured by the distance between two ratchet teeth 73. When the ratchet wheel 72 is advanced to such a position that the space 110 is opposite the cam 111 such cam and connected parts are permitted to drop thereby withdrawing the idler 118 from under the pawls 75 and 76 whereupon the said pawls are permitted to retract to such an extent as to engage a tooth 73, two teeth removed from the tooth engaged during the previous course of knitting, the result being that the ratchet wheel 72 gains one tooth. The purpose of the space 110 is to permit a change in the set-up of the pattern to be knitted, e. g. if there be sixty teeth 73 and it be desirable to repeat the pattern every fifty-nine courses, a single space 110 is provided as shown, and if the pattern be one that should be repeated every fifty-eight courses two such spaces 110 are provided in the row of circular lugs 109.

10 If the number of teeth 73 corresponds to the number of courses of the pattern to be knitted, the pins or lugs 109 may be dispensed with and a detent or lock 119 may be substituted therefor. The detent 119 is pivoted at 120 to the rod 112 and at its upper end is provided with a pro-

jection 121 which is adapted to take over the pin or screw 117 thereby locking the rod 112 in its relatively upper position, in which position the idler 118 permits the pawls 75 and 76 to move the ratchet 73 through the distance measured by adjacent teeth only during the knitting of all of the courses of the stocking. 5

If it be desirable to vary the positions of the eyelets 33, 34 with respect to the forward edge of the mouthpiece thereby to vary the feeding separation of the three threads, the pin or shaft 20 may be mounted in an eccentric 122 which may be subsequently adjusted manually or otherwise and when in the proper circumferential position may be fixed against circumferential movement as by means of a set screw 122'. 10

In Figs. 20-25 inclusive are shown various relations of two body threads 123 and 124 and two plating threads 125 and 126. In Fig. 20 the body thread 123 is shown as being knitted into 20 the fabric with plating threads 125 and 126, whereas in Fig. 21 the body thread 124 is shown as being knitted into the fabric with threads 125 and 126. In the said figures the thread 123 is shown as passing through an eyelet in the lever 21, the thread 124 is shown as passing through an eyelet provided in the lever 122, and the threads 125 and 126 are shown as passing through the eyelets 33 and 34 respectively. Thus by the construction hereinbefore described, the threads 125 and 126 may be knitted into the fabric together with either the thread 123 or the thread 124, the means for automatically turning the shaft or spindle 25 permitting the threads 125 and 126 to exchange positions at will during the knitting of the fabric. Figs. 22 and 23 correspond respectively to Figs. 20 and 21 excepting that in Figs. 22 and 23 the plating relations of the threads is shown as being different from that in Figs. 20 and 21, in that the threads 125, at one or more of the needles, is shown as being the intermediate and as having changed positions with the thread 126, the position of the threads in Fig. 22 being shown in vertical elevation in a needle hook in Fig. 25. 25

It will be understood that the plating relations of a body thread and a plating thread may be varied in any well known manner such as by specially constructed sinkers or by needle deflection to effect the changes indicated in Figs. 22-25 as compared with Figs. 20 and 21. 45

If desired tension may be applied to the threads 125 and 126 while the threads 123 and 124 are being fed to the needles substantially free from tension. 50

Although in the foregoing description and the drawings the pattern mechanism disclosed specifically in Figs. 6-11 inclusive, is disclosed as for the purpose of interchangeably positioning two plating threads with respect to the needles, 60 it is obvious that such mechanisms may be used for other purposes. 55

During heel and toe knitting the drum 14 is rendered inoperative by being swung away from the needle cylinder and for this purpose a lever 65 127 (Fig. 2), to one end of which the drum is connected, is provided. To the other arm of the lever 127 is connected a link 128 which is automatically actuated in any desired manner for withdrawing the drum to an inoperative position. 70

Means such as a bell crank lever 129 pivoted at 130 to the machine frame may be provided, such lever being for the purpose of limiting the movement of the pawl 16 so that, when the lever 129 is in the position shown in Fig. 2, said pawl 75

is adapted to advance the drum 14 through an arc measured by the length of one tooth 15. When the lever 129 is swung upon its pivot, against the tension of a spring 131, by any suitable means, the pawl 16 is permitted to rack the drum through an arc measured by the length of two teeth 15.

A cam 132 (Fig. 3) which is mounted upon a drum fixed to shaft 107, may be provided for acting upon a lever 133 pivoted at 134 to a bracket 135 connected to the machine frame. To the other arm of the lever 133 is pivotally connected a slidably adjustable link 136 to the other end of which link is pivotally connected a lever 137 pivoted intermediate its ends at 138 to any suitable support. A spring 138', connected to lever 133 and one part of link 136, maintains the two parts of said link 136 in telescopic relation. The other arm of the lever 137 is bifurcated at 139, the arms thereof straddling a pin 140 laterally projecting from a detent or lock 141 which is provided intermediate its ends with a notch 142. When the drum is advanced to such a position as to cause the cam 132 to engage and rock the lever 133 such lever is rocked against the retractile force of spring 138, the rocking of such lever causing the detent 141 to be swung upon its pivot 144 thereby elevating the shoulder defined by the notch 142 to such a position as to engage a lug 145 of the pawl carrying mechanism to prevent the pawl from advancing the drum 14. A cam or cams such as 132 may be provided for rendering the drum inoperative at any desired time such as during the knitting of a heel of a stocking.

The pawl 16 is actuated from the "104" gear 81 which carries upon one surface thereof, preferably, four pins 146 which thus engage a suitable cam 147 during the knitting of each course. The cam 147 is made fast to a lever 148 pivoted at 149 to a suitable bracket 150 carried by the machine frame. The other end of the lever 148 has pivotally connected thereto at 151 an adjustable link 152, the other end of which is pivotally connected at 153 to the pawl carrying mechanism.

In the foregoing description the threads or yarns 125, 126 have been, for convenience, referred to as "plating yarns" and the threads or yarns 123, 124 have been referred to as "body yarns"; however, when knitting a plated fabric with two or more yarns, each thread or yarn overlies the other yarn or yarns so that any one of the yarns may be considered to be a "plating yarn".

In the foregoing description, specific terms have been used for specifically describing the several elements disclosed in the drawings; however, it is not the intention to limit the scope of the invention to the precise details of construction shown and described other than as defined by the specific recitations in the claims themselves.

We claim:

1. A method of continuously knitting three threads consisting in causing one such thread to be maintained in separated plating relation with respect to the other two threads and causing such other two threads to change their relative positions with respect to each other and with respect to the thread first mentioned, and causing one or the other of the two threads second mentioned to appear on the face of the fabric and selectively causing the thread first mentioned to appear on the face of the fabric at selected wales whereby the three threads shall appear on the face of the fabric.

2. A method of knitting consisting in feeding

a body thread and two plating threads to the needles, maintaining substantially the same tension on the two plating threads and interchangeably causing first one such plating thread and then the other plating thread to appear on the 5 face of the fabric, and causing the plating thread and a body thread to interchange their positions at will, whereby reversely plated fabric may be knitted.

3. In a knitting machine, needles and means 10 for simultaneously feeding a body thread and at least two plating threads to the needles, the plating threads being fed to the needles under substantially the same tension, said means including two thread guides, in combination with means 15 for automatically interchanging the positions of the two thread guides, and other means for causing the body thread to appear on the face of the fabric in selected wales to displace either of the two plating threads. 20

4. In a knitting machine, needles and means for feeding at least one body thread and one plating thread thereto, in combination with means for adjustably positioning the plating thread thereby to permit the plating separation 25 of the two threads to be varied.

5. A knitting machine, a pattern member having indications thereon for controlling the operations of the knitting machine, such pattern member having ratchet teeth thereon in combination with two pawls for engaging the ratchet teeth and thereby advancing the member, one of the teeth of the member being a half-tooth thereby effecting the idling of one of the pawls, in combination with means adapted to idle one 35 of the pawls while permitting the other pawl to advance the pattern member to retime the same, such pattern member coming to rest when the half-tooth moves to a position opposite the re-timing pawl. 40

6. Yarn feeding mechanism for knitting machines comprising a guide for a yarn, a pair of guides for other yarns each of said pair of guides being adapted to feed its yarn to all of the needles, and means to move either of said pair 45 of guides at will, relatively to the first mentioned yarn guide, into feeding position on the same side of the said guide, whereby to ensure like association of either of said other yarns with the yarn first mentioned.

7. A knitting machine having a rotary needle cylinder and a stationary mouthpiece, yarn guides in the mouthpiece for feeding at least three yarns to the needles, two of the said guides independently feeding two of the said yarns to the needles 55 and being positioned at the same side of the guide for feeding the third yarn, the two guides first mentioned being interchangeably moved to and from feeding position with respect to the needles so that the like association of either of the said two yarns with the third yarn is ensured.

8. A knitting machine having a rotary needle cylinder and a stationary mouthpiece, yarn guides in the mouthpiece for feeding at least four 65 yarns to the needles, two of the said guides independently feeding two of the said yarns to the needles and being positioned at the same side of the guides for feeding the two other yarns, the two guides first mentioned being interchangeably 70 moved to and from feeding position with respect to the needles so that the like association of either of the said two yarns with the two other yarns is ensured.

9. A circular knitting machine having means 75

- for feeding two yarns or threads to the needles thereof, said feeding means including a rotary element the axis of which is parallel to the needles, the rotary element when in one position feeding two yarns to the needles in a plating relation and when in another position feeding the yarns to the needles in a reversed plating relation, the movements of the rotary element to and from each of its positions being upon its axis.
10. A circular knitting machine and means for feeding at least two yarns to the needles and in a plating relation, and rotary means the axis of which is parallel to the needles for changing the plating relation in which the two threads are fed to the needles, said means last mentioned including a pinion and a gear for imparting oscillatory movements to the pinion to change the plating relation of the two threads, a pattern mechanism and connections leading from the gear to the
15. pattern mechanism for controlling the oscillatory movements of the pinion thereby to determine when the plating relations of the threads shall be changed.
11. In a knitting machine, pattern mechanism and means for feeding at least two threads to the needles in addition to the ground thread and in such a manner that either of the two threads may appear at the face of the fabric, means for changing the feeding position of the two threads
20. with respect to the needles and with respect to each other including a vertically extending yarn guiding element having two yarn conducting openings therein, means for rotating said element about its axis including a gear on the element, a sector meshing therewith and mechanical connections from said pattern mechanism to said sector for imparting rotation to the element whereby the position of the said two threads may be reversed with respect to the ground thread.
25. 12. A method of knitting three threads so that any one of the three threads may optionally appear on the outer face of the fabric, said method including imposing substantially the same tension on two of the threads and less than on the other thread.
30. 13. A method of knitting three threads so that any one of the three threads may optionally appear on the outer face of the fabric, said method including feeding two of the threads to the needles in a substantially spaced relation with respect to the third thread and acting upon the third thread at selected wales so that, at the said wales, the third thread shall appear on the outer face of the fabric, the operation being such that
35. at the other wales either one of the first two threads shall appear on the outer face of the fabric, and causing the first two threads to change their position with respect to one another so that one such thread and then the other such thread shall appear on the outer face of the fabric where not displaced by the third thread.
40. 14. A knitting machine having means for feeding at least three threads to the needles, one at least of said three threads being fed to the needles in a spaced relation with respect to the other threads, means acting upon the thread feeding
45. means to cause first one and then another of the

said other threads to appear on the outer face of the fabric at certain wales, in combination with means selectively acting in such a manner that a first mentioned thread shall appear on the outer face of the fabric at selected wales.

15. A knitting machine having means for feeding at least three threads to the needles, one at least of said three threads being fed to the needles in a spaced relation with respect to the other threads, means acting upon the thread feeding means to cause first one and then another of the said other threads to appear on the outer face of the fabric at certain wales, in combination with sinkers selectively acting in such a manner that a first mentioned thread shall appear on the outer face of the fabric at selected wales.

16. A knitting machine having means for feeding at least three threads to the needles, and including a rotary member, one at least of said three threads being fed to the needles in a spaced relation with respect to the other threads, means rotating the said rotary member to cause first one and then another of the said other threads to appear on the outer face of the fabric at certain wales, in combination with means selectively acting in such a manner that a first mentioned thread shall appear on the outer face of the fabric at selected wales.

17. A knitting machine having means for feeding at least three threads to the needles, and including a rotary member, one at least of said three threads being fed to the needles in a spaced relation with respect to the other threads, means rotating the said rotary member to cause first one and then another of the said other threads to appear on the outer face of the fabric at certain wales, in combination with sinkers selectively acting in such a manner that a first mentioned thread shall appear on the outer face of the fabric at selected wales.

18. A method of feeding four threads to the needles and continuously knitting three of the said threads and causing the fourth thread to be interchangeably fed to the needles with one of the other threads, knitting two of the threads continuously and periodically changing their relative positions so that either one of the said two threads may appear on the outer face of the fabric at will and causing whichever of the first mentioned threads is being fed to the needles, to displace, on the outer face of the fabric, whichever of the two continuously knitted threads is being knitted so as to appear on the outer face of the fabric.

19. A knitting machine having pattern means for controlling various operations thereof, said pattern means including a pawl and ratchet mechanism and a movable member for rendering the pawl ineffective during the knitting of a portion of the fabric, in combination with automatically controlled means for moving the said member so that the pawl may again advance the ratchet, retiming of the operations being effected while the movable member maintains the pawl ineffective.
